X000 9798

C. M. Keller,
Making Stares.

Patented June 29, 1836.

Charles, Mr. Heller.

Sellers Patent. Patented, June 29, 1836.

The Schedule referred to in this Seller's Patent and making part of the same containing a description in the words of the said Charles, Mr. Heller himself, of his improvement in the Machinery for Sawing Belvedere.

Be it known that I, Charles, Mr. Heller, of Washington in the County of Washington and District of Columbia have invented a new and useful improvement in the Machinery for sawing Belvedere, and that the following is a full and exact description of the construction and operation of the same: reference being had to the accompanying drawings, making part of this Specification.

The improvements consist in giving to the blocks referred to in the timber being sawed into slates, a double motion. One, a right angle to the other, the sum of which will produce the shape desired for a Belvedere, and also in imparting to the gang of saws a circular motion, which will accommodate their direction to the figure formed by the compound motion of the blocks.

In the accompanying drawings, Figure 1 is a plan of the machine. Figure 2, a side elevation. Figure 3, a cross section, just in front of the fender posts. The other Figures will be referred to under their appropriate heads.

The same letters are indicative of the same parts in all the Figures.

Scale of drawing 1/2 in. to the foot.

A represents the joists of the building, to which the end B of the machine is firmly secured, by bolts or otherwise. C, C, are the fender posts and D, D, the carriage ways. These parts, constituting the frame work of the machine, should be made of strong timber or cast iron and secured together in such a manner as to prevent as much as possible, all jarring or trembling motion. B, is a carriage running in a straight line in the ways D, D, confined in its oscillating motion by plates A, A, to which are attached two metallic plates F, F, seen in section at figures 4, 5, & 6, each having a slot h. On these plates are placed the head and tail of G, G, having projections e, e, on fig. 7, on their under sides fitting into the slots h, h. The upper surface of the plates and the under surface of the head and tail

blocks should be planished, and the slots b, b, and projections c, c, should be made to fit truly, so as to cause the head and tail blocks to slide easily and without warbling, at right angles to the carriage B. The eyes on the head and tail blocks, and by which the blocks or blocks designed to stay, are made fast, are seen at e, f, and may be altered at pleasure, as the mode of fastening, is not material.

The carriage B, may be moved back and forth in the same manner as the carriage of a saw mill, viz. by a wag wheel, pinion, and a track. The wag wheel is represented at H. There is a slot in each end of the head and tail blocks, in which are fixed the spindles of two rollers g, g, with sets and nuts for the purpose of setting them. These rollers are each side of a saw guide I, I. These guides are made of iron, and bolted to a timber of hard wood, which is let into the bed of the machine, and regulated by wedges. To each end of the carriage, is attached an arm of wood, extending beyond the guides, to which the saw guide bar, is bolted. The guide K is either cast with the bar, or attached to it so as to run with it. The shape of the saw guide will always be governed by the saw guides, and length of the bar (to be hereafter described) which gives motion to the saw. In side L, is provided with two sets of rollers h, h, at one end, playing on each side of the saw guide, and two others i, i, playing on each side of the bar M. This arm moves in an upright N, see fig. 8.

The saw gate O, which is made of cast iron, and works in blocks P, P, P, which are bolted to the guides, is put in motion by a pitman which connects it with the moving power. There are two cross heads Q, Q, affixed to gate. The metal on the bottom is firmly bolted in place, and there is a top metal to slide up or down, and regulated by the screw f, f, and is provided at each end with set screws K, K. These cross heads are made in two pieces, as seen at o, and kept together by the screw bolts U. Six holes, very accurately bored through the cross heads, and in which the saw hangers work, are seen at m, m, in these hangers, the pins s, s, are attached, see fig. 10. The hangers in the cross heads, have heads turned on them, as at o, and these are then upon holes, bored out on the ends, furnished with nuts and washers, (see p fig. 10) and

small feather which prevents the vibratory motion of the hangers from affecting the scions. The hangers q, q , have round pins, working into holes made in the connecting bars R, R.

On one side of the saw gate is a tumbling shaft S, with guides on each end working in holes made in the cross heads, on a stem with the holes in which the hangers are worked. There are two arms S, S, extending from the tumbling shaft, to the end of which is attached the ground bar of iron M, which plays between the rollers L, L, before described. At each extremity of the tumbling shaft is a bar L, L, with a pin, working into a hole in the end of the connecting bar.

The saws N, N, are connected with the hangers by pins, as seen at U, U, fig 10. Operation 11. The blocks of wood being cut to the length required for slaves in width, sufficient to prevent the saws from cutting out at the sides, and not more than a little more than the width of a slave, are successively placed on the head and tail blocks, and secured in their place by the dogs. The saw gate is set in motion, and, when in readiness, the block is impelled against the saws by the motion of the carriage, which is in a direct line towards them. The head and tail blocks, however, are movable in the slots, which are at right angles with this, motion of the carriage, and are governed in this their lateral motion by the shape of the curve of the slave guides.

As the first rollers in the head and tail blocks are on each side of the slave guides, it is evident that as the carriage advances these blocks, together with the block which is changing its character into slaves, has a motion at right angles to the motion of the carriage, the sum of which two motions describes a curve similar to that of the slave guides, and that the saws by cutting this curve the slaves into the block of wood in the form of slaves.

The change of direction or vibration of the saws which accommodates them to the above described curve is obtained by means of the saw guides K, which being firmly connected with, and moved by the carriage B, give motion to the bar M on the tumbling shaft, by means of the slides L, which motion causes the saws to vibrate or change the direction in which they cut according to the shape of the guides K.

• At the curve given to the slaves is produced by two motions at right angles.

with each other, any number of saws may be used in a gang, without affecting the curve, which will uniformly be the same, or may be altered at pleasure by changing the shape of the staves guides and saw guide. The thickness of the staves will be regulated by the distance between the saws.

One, two or more blocks may be cut throughout the same time, according to the length of the saws.

The construction of the machine, can be altered, without affecting its principles.

What I claim as my invention is the Double Motion, consisting of an angle to the other, given to the block of wood, by which the curve of the staves, is produced, and also the giving to a gang of saws, a vibratory motion, which accommodates them to the curve produced, by the compound motion, in combination.
